SAFETY STOP MECHANISM FOR WARP DRAWING-IN MACHINES

Russell P. Drake, Caledonia, Ill., assignor to Barber-Colman Company, Rockford, Ill., a corporation of Illinois

Application May 3, 1946, Serial No. 666,989

21 Claims. (Cl. 28—46)

1

The invention pertains to warp drawing-in machines and has particular reference to a safety stop mechanism for machines of the type disclosed in my copending application, Serial No. 533,160, filed April 28, 1944, now Patent Number 2,400,342. That machine embodies a pattern control mechanism in which a perforated pattern sheet, preferably of metal, selectively controls the operation of heddle turning worm shafts and release key shafts through the medium of a plurality of driving gears shifted into engagement with an actuating rack by movement of the pattern against a series of control or feeler elements, the arrangement being such that when the pattern is moved toward the feeler elements certain of the latter are permitted to remain idle by passage through holes in the pattern sheet while others are actuated by engagement with imperforate portions of the sheet so as to cause the corresponding driving gears to be shifted into mesh with the rack. In their inactive positions, the driving gears are held locked against rotation by a positive clutch connection with stationary clutch elements, and the driving gears when shifted move out of engagement with such clutch elements and into engagement with the rack.

It sometimes happens that the release key shafts and turning worm shafts to be operated in one cycle are subjected to forces incident to operation in the preceding cycle and tending to rotate the same so as to increase substantially the force required to disengage the drive gears from their respective clutch elements. Moreover, such rotative forces imposed upon the driving gears tend to impart a partial rotative movement to the gears as permitted by a small amount of play in the clutch connections, thereby causing a slight displacement of the gears relative to the actuating rack. In such circumstances, an abnormal load may be imposed upon the pattern sheet in actuating the feeler elements, sufficient to cause the latter to pierce the pattern sheet and fail properly to move the gears clear of the stationary clutch elements while at the same time partially engaging with the rack with the result that breakage of the parts occurs in the ensuing actuation of the rack. With this in view, the primary object of the invention is to provide a safety stop mechanism for interrupting the operation of the machine in the event that any of the driving gears selected for movement into engagement with the actuating rack fail for any reason to be shifted by actuation of

the pattern sheet clear of their respective clutch elements.

A further object is to provide a safety stop mechanism simple and inexpensive in construction and capable of being reset easily to restore the parts to normal condition.

The objects of the invention thus generally set forth, together with other and ancillary advantages, are attained by the construction and arrangement shown by way of illustration in the accompanying drawings, in which:

Fig. 1 is a fragmentary plan view of a warp drawing machine showing in particular the pattern control mechanism and driving mechanism together with a safety stop mechanism constructed in accordance with my invention.

Fig. 2 is a vertical sectional view taken approximately in the plane of line 2—2 of Fig. 1 but on an enlarged scale.

Fig. 3 is a fragmentary vertical sectional view illustrating the selective actuation of the feeler elements by the pattern sheet.

Fig. 4 is a vertical sectional view taken approximately in the plane of line 4—4 of Fig. 1, also on an enlarged scale.

Fig. 5 is an enlarged section taken approximately in the plane of line 5—5 of Fig. 1.

Fig. 6 is an enlarged plan section through a portion of a connecting link forming a part of the clutch operating means for the power drive mechanism and illustrating the construction whereby the latter mechanism is actuated to stop the machine.

Fig. 7 is a similar view but showing the parts in a different relation.

Fig. 8 is a similar view showing the parts in still another relation, namely, that occupied in the operation of resetting the safety mechanism.

Referring first to Figs. 1, 2 and 3, I have shown my invention as applied to a machine of the type shown in my said copending application to which reference is made for a detailed disclosure of the construction and mode of operation. Briefly, the machine comprises a plurality of pairs of release

key shafts 10 and turning worm shafts 11 (see Fig. 5) connected by gearing 12 for operation selectively under the control of a pattern sheet 13. The latter passes over a perforated drum 14 (Fig. 3) and is provided with horizontal rows of holes 15, leaving imperforate areas 16. The holes are positioned so as to register with holes 17 in the drum, there being one hole in the drum for each of a horizontal series of control or feeler elements 18.

In the operation of the machine, rotative

movements are imparted to the drum 14 by a cam 19 (Fig. 2) acting through a bell crank lever 20 carrying a gear segment 21 arranged to mesh with a gear 22 rigid with the drum. The gear segment 21 meshes with the gear 22 when the drum is in its rearmost position shown in Fig. 2. After a stepping movement is imparted to the drum by the cam 19 and bell crank 20, the drum is rocked forwardly by means of a cam 23 operating through an arm 24 carrying roller followers 25 engaging with the cam. The arm 24 has a pair of arms 26 rigid therewith in which the drum is rotatably supported.

The feeler elements 18 have extensions 27 provided with rack teeth 28 meshing with gears 29. The latter mesh with rack teeth 30 on shifter bars 31 urged by springs 32 in a direction to oppose movement by the pattern sheet. At their free ends, the bars 31 carry shifting members 33 (Fig. 5) engaging in grooved collars 34 splined on shafts 35 rigid with the respective turning worm shafts 11. The collars carry pinions 36 which normally occupy positions in disengaged relation to an actuating rack 37, and the arrangement is such that when one or more of the shifter bars are moved by the pattern 13 in the actuation of the drum 14, the corresponding gears 36 are moved into engagement with the actuating rack 37 for operation thereby.

Movements are imparted to the actuating rack 37 in timed relation to the actuation of the shifter bars by the pattern and drum, by means of a cam 38 (Fig. 2) acting upon a roller follower 38a rigid with the rack 37. The cam 38 is mounted on a shaft 39 which also carries the cam 19 for imparting stepping movements to the pattern drum, the cam 23 for rocking the drum being mounted on a shaft 40 geared to the shaft 39.

As shown in Fig. 1, the shaft 39 is arranged to be driven by bevel gearing 41 from a power driven shaft 42 connected by spur gearing 43 with a drive shaft 44. The latter is actuated by a motor 45 through a belt connection 46, a differential drive unit 47 and a combined clutch and brake unit including a clutch 48 and a brake 49, and arranged for operation in one direction to engage the clutch and in the opposite direction to disengage the clutch and apply the brake. The unit is arranged for actuation by a lever 50 connected by a link 51 with a bell crank 52 to which is pivoted a shifter rod 54 extending to the front of the machine and connected to a hand lever 55.

In their disengaged positions, the gears 36 and therefore the turning worm shafts 11 are held stationary by the interengagement of tongues 56 on the hubs of the gears 36 with notches 57 in locking clutch elements 58, the latter being mounted upon a frame member 59. In the normal operation of the machine, the gears 36 are shifted selectively as determined by the nature of the pattern into engagement with the actuator rack 37 so that in the ensuing movement of the rack, selected ones of the turning worms and therefore of the release keys are operated.

It will be appreciated that such shifting movement of the gears 36 by the pattern sheet acting through imperforate areas thereon engaging the control elements 18, necessitates that the gears 36 be relatively free to move. Accordingly, when one of the turning worm shafts 11 is subjected to a rotative force tending to rotate the corresponding drive gear, the frictional resistance between its tongue 56 and the locking clutch element 58 therefor may be increased to an extent

such that the pattern sheet is incapable of bearing the load imposed thereon with the result that the corresponding feeler element will pierce the sheet after having effected partial intermeshing of the drive gear with the actuator rack. Moreover, the tongues 56 are in practice tapered for purposes of easier entry into the notches 57 while the abutting ends of the intermeshing teeth of the two gear elements are somewhat beveled to facilitate interengagement. Consequently, as the tongue of a gear element moves out of its notch, a small amount of play develops such that if the gear is subjected to a rotative force a slight displacement of the gear relative to the rack will occur permitting only partial engagement of the gear with the rack so as to block the feeler elements for movement by the pattern sheet.

In order to avoid damage to the machine resulting from failure of the selected drive gears to be shifted properly under all conditions, the clutch elements 58 are, in accordance with the present invention, mounted so as to be capable of yielding in the event of partial engagement of the gear element with the rack, and such yielding movement is utilized to bring the machine to a stop. For this purpose, each of the locking elements 58 is operatively connected with a pivoted arm 60 (Fig. 4) having a tongue 61 normally engaging in a groove in the locking element and urged by a spring 62 against an adjustable stop 63. Each locking element 58 is in the form of a disk and when the latter is rotated against the action of its spring the tongue 61 becomes disengaged from its groove and rides on the periphery of the disk.

A control device in the form of a slide bar 64 is arranged for operation by any one of the arms 60. Thus the bar 64 has a series of depending lugs 65, one for each of the arms 60, and also an operating member 66 for a switch generally designated 67 controlling the energization of a solenoid 68 (Figs. 1 and 6). The switch 67 has a spring pressed plunger 69 engaged by the operating member 66 on the slide 64, and the arrangement is such that when any one of the locking members is rotated due to partial engagement only with the rack, its arm 60 engages a lug 65 on the slide bar, shifting the bar to the left (Fig. 4) so as to operate the switch 67.

Energization of a solenoid 68 under the control of the switch 67 is utilized to disengage the clutch 48 and apply the brake 49, thus bringing the machine to a stop. Such automatic actuation of the clutch by the solenoid is accomplished by a special construction of the operating rod 54 such that it is capable of contracting longitudinally under the force of a spring 70 controlled by a detent 71 operatively associated with the solenoid through the medium of a linkage 72.

The rod 54 in the present instance is made in two sections 54a and 54b (Fig. 6) coupled by a sleeve 73 having one end rigid with the section 54b and the other end slidable relative to the section 54a. The latter has fixed thereto a plunger 74 slidable within the sleeve 73. The spring 70 is also disposed within the sleeve in encircling relation to the rod section 54a and one end of the spring bears against the plunger 74 and the other against a flanged end of the sleeve. The rod section 54b has a plug 75 rigid therewith and screw threaded into the sleeve so as to form a connection with the sleeve.

When the machine is in operation, with the clutch engaged, the plunger 74 is engaged by the

detent 71 so as to hold the plunger against movement in the sleeve by the spring 70 and maintain the latter under compression, the detent being slidable in a lateral extension 76 of the sleeve and against the action of a spring 77. The rod section 54a carries a stop collar 78 engaging with a stationary frame member 79 so that movement of the rod section 54a in a clutch engaging direction (to the left in Fig. 6) is limited by the collar. Accordingly, when the detent 71 is withdrawn upon energization of the solenoid, the spring 70 acts upon the sleeve to move it to the right in Fig. 6, carrying with it the rod section 54b and actuating the bell crank 52 and lever 50 so as to disengage the clutch 48 and engage the brake.

49. In Fig. 6, I have shown in broken lines the position occupied by the collar 78 when the hand lever 55 is in the position shown in Fig. 1. When the hand lever is shifted to engage the clutch, the stop collar 78 is moved into the full line position of Fig. 6.

To reestablish the normal connection between the rod sections 54a and 54b it is only necessary to impart a sharp movement to the hand lever 55, drawing the rod section 54a to the right against the action of the spring 70, the moment of inertia being sufficient to hold the sleeve 73 and associated parts against movement while the spring is contracted sufficiently to permit reentry of the detent 71 by its spring 77. As seen in Fig. 8, the extent of such movement imparted to the plunger 74 by a sudden movement imparted to the rod section 54a is limited by a shoulder 80 so positioned that the plunger moves free of the detent.

Summarizing the operation, movement of the drum 14 by cam 23 acting upon roller followers 25 carries the pattern sheet 13 toward the control elements 18 and such of the latter elements which are presented to the imperforate areas 16 of the pattern sheet are carried forwardly with the drum. Thus the shifter bars 31 are actuated against their springs 32 so as to draw the driving gears 36 into engagement with the actuating rack 37 and, in the ensuing movement of the rack, turning movements are imparted to selected ones of the turning worm shafts and release key shafts. In such movement of the selected gears 36, the corresponding tongues 56 move out of engagement with their respective notches 57 in the locking elements 58 as the gears move into complete mesh with the actuating rack 37.

In the event that any of the selected shafts is subjected to a rotative force tending to rotate one of the gears 36, thereby resisting or preventing disengagement of the gear from its holding or locking element 58, the pattern sheet may be incapable of withstanding the pressure upon the corresponding feeler element with the result that the feeler element will pierce the sheet and move a distance sufficient only to partially disengage the tongue 56 from the positioning element 58 and yet sufficient to cause the gear 36 to engage partially the rack 37. When this occurs, a rotative force is applied to the corresponding positioning element but since this element is yieldable, no damage to the machine results. Moreover, the yielding of the element 58 imparts a swinging movement to the corresponding lever arm 60 and thereby to the control slide 64 and member 66 so as to operate the plunger 69 of switch 67. In the ensuing energization of solenoid 68, detent 71 is withdrawn so as to allow contraction of the control rod by the spring 70 and operation of the main drive clutch. In this

operation, the detent 71 releases the sleeve 73 for movement to the right under the action of the spring 70 (Figs. 6 and 7), the rod section 54a, and therefore the plunger 74, being held stationary by the stop 78. Such movement of the sleeve is transmitted to the rod section 54b and thereby to the bell crank 52 and clutch operating lever 50 so as to disengage the clutch and apply the brake. After the abnormal condition encountered has been corrected, the normal operative connection between the two sections of the rod 54 is reestablished by moving the hand lever 55 sharply forwardly (Fig. 1) so as to compress the spring 70 sufficiently to permit reentry of the detent 71.

I claim as my invention:

1. In a warp drawing machine having a shaft to be operated, a power driven actuator, a drive element shiftable to establish a driving connection between said shaft and said actuator, and pattern actuated means for shifting said element; a safety stop mechanism including a yieldable member movable by said actuator upon a partial shifting only of the drive element by the pattern actuated means, and means responsive to such yielding movement of said member to interrupt the operation of the machine.
2. In a warp drawing machine having a shaft to be operated, a power driven actuator, a drive element shiftable to establish a driving connection between said shaft and said actuator, a locking member normally holding said drive element against rotation, said drive element having a disengageable connection with said member, and pattern actuated means for shifting said element out of engagement with said locking member and into engagement with said actuator, said locking member being mounted for yielding movement upon failure of the drive element to move out of engagement with said actuator.
3. In a warp drawing machine having a shaft to be operated, a power driven actuator, a drive element shiftable to establish a driving connection between said shaft and said actuator, a locking member normally holding said drive element against rotation, said drive element having a disengageable connection with said member, pattern actuated means for shifting said drive element out of engagement with said locking member and into engagement with said actuator, said locking member being rotatable by the drive element in the event of movement of the latter into only partially engaged relation to the actuator, and means responsive to such rotation of the locking member to interrupt the operation of the machine.
4. In a warp drawing machine having a shaft to be operated, a power actuated rack bar, a drive gear splined on said shaft and shiftable into and out of mesh with said rack bar, a locking member normally holding said gear and thereby said shaft against rotation, said gear having a disengageable positive clutch connection with said member, and pattern actuated means for shifting said gear out of engagement with said locking member and into mesh with said rack bar, said locking member being yieldable upon movement of the drive gear into partial engagement only with said rack bar.
5. In a warp drawing machine having a plurality of shafts to be operated selectively, a power driven rack, a shiftable drive gear for each of said shafts movable into and out of driving engagement with said rack, a locking member for

each drive gear, said gears having disengageable clutch connections with their respective locking members, pattern actuated means for shifting the drive gears into engagement with said rack selectively, said locking members being mounted for rotational movement with their respective drive gears upon partial engagement only with said rack, and means operative upon said rotational movement of any one of said locking members to interrupt the operation of the machine.

6. In a warp drawing machine having a plurality of shafts to be operated selectively, a common actuator for said shafts, a power drive mechanism having a disengageable connection with said actuator including a control member, a drive element for each shaft shiftable into and out of engagement with said actuator, and means operative automatically upon movement of any one of said drive elements into partial engagement only with the actuator to actuate the control member so as to disengage said driving connection.

7. In a warp drawing machine having a plurality of shafts to be operated selectively, a rack bar common to said shafts, power drive mechanism for said bar including a clutch and an operating member therefor, a drive gear for each shaft shiftable into and out of engagement with said rack bar, and means operative automatically upon movement of any one of said gears into partial engagement only with the rack bar to actuate said clutch operating member to effect stoppage of the machine.

8. In a warp drawing machine having a plurality of shafts to be operated selectively, a common actuator for said shafts, power driven mechanism for said actuator including a clutch and an operating member therefor, a drive element for each shaft shiftable into and out of engagement with said actuator and means operative automatically upon movement of any one of said drive elements into partial engagement only with the actuator to actuate said clutch operating member, said means comprising a member engageable by each of the drive elements when in wholly or partially disengaged relation to the actuator, a control device arranged for actuation by any one of said members, and means controlled by said device for actuating said clutch operating member.

9. In a warp drawing machine having a plurality of shafts to be operated selectively, a common actuator for said shafts, power driven mechanism for said actuator including a clutch and an operating member therefor, a drive element for each shaft shiftable into and out of engagement with said actuator and means operative automatically upon movement of any one of said drive elements into partial engagement only with the actuator to actuate said clutch operating member, said means comprising a member engageable by each of the drive elements when in wholly or partially disengaged relation to the actuator, a control device arranged for actuation by any one of said members, and electrically operated means controlled by said device for actuating said clutch operating member.

10. In a warp drawing machine having a plurality of shafts to be operated selectively, a rack bar common to said shafts, power drive mechanism for said actuator including a clutch and an operating member therefor, a drive gear for each shaft shiftable into and out of engagement with said rack, and means operative automatically upon movement of any one of said

5 gears into partial engagement only with the rack to actuate said clutch operating member to effect stoppage of the machine comprising a plurality of locking members engageable by the respective drive elements when in disengaged relation to the rack, and a control device arranged for actuation by any one of said members when its corresponding drive gear is in partial engagement only with the rack.

10 11. In a warp drawing machine having a plurality of shafts to be operated selectively, an actuating rack common to said shafts, power drive mechanism for said actuator including a clutch and an operating member therefor, a drive gear for each shaft shiftable into and out of engagement with said actuator, a plurality of locking members, one for each of said drive gears, each of said gears having a positive clutch connection with its locking member for rotation of the member by the rack upon partial disengagement only of the gear with respect to its locking member, a control device common to said locking members and arranged for actuation by any one of them, and means operable by said control device to actuate said clutch operating member.

15 12. In a warp drawing machine having a plurality of shafts to be operated selectively, an actuating rack common to said shafts, power drive mechanism for said actuator including a clutch and an operating member therefor, a drive gear for each shaft shiftable into and out of engagement with said actuator, a plurality of locking members, one for each of said drive gears, each of said gears having a positive clutch connection with its locking member for rotation of the latter by the rack upon partial disengagement only of any drive gear with respect to its locking member, a control device common to said locking members, a spring actuated lever operatively connected with each of said members and operatively associated with said control device to actuate the latter upon movement of the lever by its corresponding member, and means operable by said control device to actuate said clutch operating member of the power drive means.

20 13. In a warp drawing machine having a plurality of shafts to be operated selectively, an actuating rack common to said shafts, a drive gear for each shaft shiftable into and out of engagement with said actuator, a plurality of locking members, one for each of said drive gears, each of said gears having a positive clutch connection with its locking member for rotation of the latter by the rack upon partial disengagement only of the gear with respect to its locking member, a control device common to said members, and a spring actuated lever operatively connected with each of said members and associated with said device to actuate the latter upon movement of a lever by its corresponding member.

25 14. In a warp drawing machine having a power drive mechanism including a clutch, clutch operating means including a longitudinally contractible link having two aligned sections, a detent mounted on one section for normally holding the two sections in extended relation and a spring for effecting relative movement between said sections so as to contract the link upon release by said detent, said link being connected with said clutch to actuate the same upon contraction by said spring.

30 15. In a warp drawing machine having a plurality of shafts to be operated selectively, a common actuator for said shafts, a power drive mechanism for said actuator including a clutch,

a drive element for each shaft shiftable into and out of driving engagement with said actuator, a control device shiftable upon movement of one of said drive elements into partial engagement only with the actuator, manually operable means for shifting said clutch including a member connected with the clutch, spring means for shifting said member in a clutch disengaging direction, a detent normally holding said spring means ineffective, and means responsive to the movement of said control device to release said detent.

16. In a warp drawing machine having a plurality of shafts to be operated selectively, a common actuator for said shafts, a power drive mechanism for said actuator including a clutch, a drive element for each shaft shiftable into and out of driving engagement with said actuator, a control device shiftable upon movement of one of said drive elements into partial engagement only with the actuator, clutch operating means comprising a member operatively connected with the clutch, a second member, a spring interposed between said members and a detent releasably holding said members against relative movement by said spring, and means responsive to the movement of said control device to release said detent, said members being operative by said spring upon release of said detent to effect the disengagement of said clutch.

17. In a warp drawing machine having a plurality of shafts to be operated selectively, a common actuator for said shafts, a power drive mechanism for said actuator including a clutch, a drive element for each shaft shiftable into and out of driving engagement with said actuator, a control device shiftable upon movement of one of said drive elements into partial engagement only with the actuator, clutch operating means including a longitudinally contractible link having two alined sections, a detent normally holding the two sections in extended relation, a stop for one of said sections, and a spring coacting with said stop to effect relative movement between said sections so as to contract the link upon release by said detent, said link being connected with said clutch to actuate the same upon contraction by said spring, and means responsive to the movement of said control device to release said detent to effect contraction of said link.

18. In a warp drawing machine having a plurality of shafts to be operated selectively, a common actuator for said shafts, a power drive mechanism for said actuator including a clutch, a drive element for each shaft shiftable into and out of driving engagement with said actuator, a control device shiftable upon movement of one of said drive elements into partial engagement only with the actuator, clutch operating means including a longitudinally contractible link having two alined sections, spring means tending to move said two sections into extended relation and a detent for holding said sections against move-

ment by said spring means, said link being connected with the clutch to actuate the same upon contraction by said spring means, a solenoid for actuating said detent, and a control switch for the solenoid responsive to the movement of said control device.

19. In a machine for operating upon warps, a plurality of shafts to be operated selectively, an actuator common to said shafts, a power drive mechanism having a disengageable driving connection with said actuator, and a manually operable device for controlling said connection comprising two members mounted for relative movement, means releasably locking said members against relative movement, said device being operative manually when its members are thus locked to cause engagement of the driving connection, and spring means operative upon release by said locking means to effect relative movement between said members in a direction to disengage said driving connection.

20. In a warp drawing machine have a drive mechanism including a clutch, a manually operable clutch controller, and a safety release mechanism, two members respectively connected with the clutch and with the controller, an abutment on the controller member and an abutment on the clutch member, a compression spring interposed between said abutments, a releasable detent arranged for actuation by said safety release mechanism and normally locking said two members together for movement in unison with said spring under compression, and means for limiting movement of the control member in a clutch engaging direction whereby to render said spring operative upon release of the detent to shift the clutch member relative to the controller member to effect disengagement of the clutch.

21. In a machine for operating upon warps a drive mechanism including a clutch, a manually operable clutch controller and a safety release mechanism, an operative connection between said controller and said clutch comprising two members respectively connected with the clutch and with the controller, means including a spring and a releasable detent normally locking said two members together for movement in unison, said detent being operatively connected with the safety release mechanism for actuation thereby.
